UNITED STATES PATENT OFFICE

NEIL GRAY, OF DAYTON, OHIO, ASSIGNOR OF FORTY-NINE ONE-HUNDREDTHS TO
ALBERT O. KASMIKSY, OF DAYTON, OHIO.

REDUCING-VALVE.

1,176,050.

Specification of Letters Patent. Patented Mar. 21, 1916.

Application filed January 9, 1915. Serial No. 1,311.

To all whom it may concern:

Be it known that I, NEIL GRAY, a citizen of the United States, residing at Dayton, in the county of Montgomery and State of Ohio, have invented certain new and useful improvements in Reducing-Valves; and I do declare the following to be a full, clear, and exact description of the invention, such as will enable others skilled in the art to 5 which it appertains to make and use the same, reference being had to the accompanying drawings, and to the letters and figures of reference marked thereon, which form a part of this specification.

15 This invention relates to new and useful improvements in reducing valves. It is well known that valves of this type are placed in a pipe line and are instrumental in reducing steam or air under a high pressure on one 20 side of the valve to a low pressure on the other side of the valve.

The object of the present invention is to provide a device of this type which is simple in construction and efficient in operation. To 25 the above end the device is entirely springless and operates entirely automatically when once set.

Referring to the accompanying drawings, Figure 1 is a side elevation of my improved 30 reducing valve; Fig. 2 is a section on the line *a—a* of Fig. 1; and Fig. 3 is a detail sectional view of the connection between the adjusting spindle and the leverage system.

In the specification and drawings, similar 35 reference characters indicate corresponding parts.

Referring more particularly to the drawings, 1 represents a valve casing provided with upper and lower valve seats 2 and 3. 40 The valve casing 1 is provided with a flange 4 by means of which the valve is connected to a high pressure pipe, not shown. The casing 1 is also provided with a flange 5 by means of which the valve is connected to a 45 low pressure pipe 6. Adapted to seat on the valve seat 2 is a valve disk 7 which is connected by a stem 8 with a valve disk 9 adapted to seat on the seat 3. The area of the valve disk 7 is somewhat larger than the 50 area of the valve disk 9 which arrangement allows the high pressure medium to tend to elevate the valve disks off of their seats. The valve disks 7 and 9 are, however, automatically regulated by the pressure within 55 the pipe 6 as follows: Pivotaly connected at

10 to the valve disk 7 is a stem 11 which extends out of a stuffing gland 12 where it is pivotally connected at 13 to a lever 14 pivoted at 15. The pivot 15 is mounted in a bracket 16 extending from a frame 17 60 mounted on a valve cap 18 attached to the valve casing 1. The lever 14 is guided at its outer end by a frame 19 which extends from the valve cap 18. Whenever the lever 14 is rocked, the valve disks 7 and 9 are elevated and lowered. The lever 14 is rocked in one direction by the high pressure medium, such as steam or air, when the valves are opened and is rocked in the other direction 65 to close the valve by a piston 20 mounted in a cylinder 21. The cylinder 21 is provided with a liner 22 and a cap 23 and is supported by the frames 17 and 19. The piston 20 is connected with the lever 14 by a connecting rod 24 pivoted at 25 to the piston 70 and at 26 to a block 27 slidably mounted in the lever 14. The movement of the piston 20 in one direction is controlled by the high pressure medium through the valve disks 7 and 9, the stem 11, the lever 14 and connecting 75 rod 24 but is moved in the opposite direction by the pressure of the medium above the piston in a chamber 30 above the piston. The pressure of the medium within the 80 chamber 30 is maintained uniform with a pressure within the low pressure pipe 6 through the agency of a connecting pipe 28 which is tapped into the pipe 6 and the cylinder 21 above the piston 20. The pipe 28 is provided with a valve 29 which may be 85 closed when it is desired to place the reducing valve out of operation. Whenever the 90 pressure in the pipe 6 elevates above a predetermined point, the pressure in the chamber 30 will push the piston 20 downward which will in turn close the valve disks 7 and 9 thereby reducing the pressure in the pipe 6. When the pressure in the pipe 6 falls below the predetermined point, the high 95 pressure media will elevate and open the valve disks 7 and 9 thereby maintaining a constant pressure within the pipe 6. The ratios of the high and low pressures may be regulated by shifting the block 27 along the 100 lever 14 thereby varying the leverage between the piston 20 and the valve disks 7 and 9. The block 27 is shifted along the lever 14 by an adjusting spindle 31, one end of 105 which is attached to the block 27 by a head 32 and a nut 33 which permits the spindle 110

to rotate within the block 27. The end of the spindle 31 opposite the head 32 is mounted in a nut 34 which is rigidly secured in the outer end of the lever 14 by a cap screw 35. 5 The same end of the spindle 31 is provided with a hand wheel 36 by means of which the spindle 31 may be rotated. By rotating the hand wheel 36, the spindle 31 will move the block 27 along the lever 14 to adjust the leverage between the piston 20 and the valve disks 7 and 9. When the block 27 is near the pivot 15, the pressures will be nearly equalized but the farther the block 27 is removed from the pivot 15 the greater will be the 15 ratio between the pressure of the media on both sides of the valve.

It will be seen that by thus constructing a reducing valve, a device is secured which is simple in construction and efficient in operation.

Having described my invention, I claim.

1. In a valve structure of the character specified, the combination of a valve casing, a stationary cylinder having a reciprocable piston therein, a communication between the outlet of said valve casing and said cylinder, an unbalanced valve in said casing consisting of two disks united to a common stem and the area of one being slightly greater

than that of the other, a lever to which said valve is pivoted, a shiftable fulcrum block mounted in said lever and to which the connecting rod of said piston is pivoted, and an adjusting screw mounted in said lever and connected to said fulcrum block, substantially as specified.

2. In a pressure-reducing valve, the combination of a frame, a stationary cylinder mounted on said frame and a reciprocable piston therein, a lever pivoted to said frame, 40 a connecting rod pivoted to said piston, a slideable member mounted in said lever and to which said connecting rod is pivoted, an adjusting screw connected to said slideable member and supported by said lever, a valve 45 casing upon which said frame is supported, the valves 7 and 9 and their seats within said casing, and a pivotal connection between the common stem of said valves and said lever, said pivotal connection being adjacent 50 to the pivotal connection of said lever with said frame, substantially as specified.

In testimony whereof I affix my signature, in presence of two witnesses.

NEIL GRAY.
